PROPELLION DEVICE

George S. Nelson, Salt Lake City, Utah

Application September 11, 1936, Serial No. 100,309

7 Claims. (Cl. 115—15)

This invention relates to improvements in propulsion devices for pumping liquids and for propelling boats; and the objects of my improvement are, first, to provide more efficient and less 5 expensive means for pumping liquids, and for propelling boats; second, to provide means for propelling boats in shallow water without the usual danger of damaging the propelling device; and third to simplify pumping devices and 10 boat propelling mechanisms.

I attain these objects by mechanism illustrated in the accompanying drawing, in which—

Figure 1 is a vertical section of a simple form of the device.

Figure 2 is a vertical section of a form of the device wherein certain automatic features are incorporated.

Figure 3 is a vertical section on line A—A in Figures 1 and 2.

Figure 4 is an enlarged part section through the upper and foreward part of the propulsion tube, showing stoppers 30 and 35 more in detail.

Similar numerals refer to similar parts throughout the several views.

In the present invention a propulsion tube 1 comprising an elongated expansion chamber 2, an elongated momentum chamber 3 which also serves as an inertia chamber, an inlet 4, an outlet 5, and a diaphragm 6, is immersed in a liquid 7. Diaphragm 6 is preferably a flexible, elastic and good insulating material.

Near the foreward, or inlet, end of tube 1 another tube 8, such as a steam tube, connects propulsion tube 1 to boiler 9. Boiler 9 is supported by legs 10, and is provided with a firebox 11, and is used for producing a gas under pressure in the usual manner for boilers.

A cutoff valve is connected in tube 8. Means such as valve 13 in fuel feed tube 14 is provided 40 to regulate the flow of fuel from fuel reservoir 15 to firebox 11. Throttle 16 may be used to control valve 13. Similarly valve 12 may be operated by handle 17.

When the device is being used for propelling a 45 boat the intake end 4 of the propulsion tube 1 is placed foreward.

The device illustrated in Figure 1 will operate as follows:

The liquid in boiler 9 is heated until a high 50 gas pressure is created in said boiler. Valve 12 is then opened for a moment thereby allowing a quantity of compressed gas to force diaphragm 6 down to position 6a, thereby closing off the intake end 4 of tube 1. In Figure 1 the foreward 55 edges of diaphragm 6 are tightly attached to

the upper side of expansion chamber 2 as indicated in Figure 3. As the compressed gas in expansion chamber 2 expands, diaphragm 6 will assume a series of positions indicated successively by 6a, 6b, and 6c and the fluid in tube 1 will be forced rearward and the boat will be propelled foreward with an equal force. The inertia of the mass of water in tube 3 will provide an effective force to back up the propelling force in tube 2.

When the diaphragm is in position 6c in Figure 1 the used gas will be exhausted. Diaphragm 6 is preferably stretched tightly across the upper part of tube 2 so that it will return more readily to its upper position after the gas is exhausted, thereby allowing a fresh supply of liquid to be drawn in through intake 4. Momentum tube 3 will assist in drawing in a fresh supply of water at intake 4 because the momentum of the mass of liquid which has been caused to move rearward in tube 3 will create a partial vacuum in tube 2 and thereby draw in more liquid. When tube 1 is again filled with liquid, valve 12 may again be opened for a moment and the propelling action will be repeated. Clearly the propelling 25 action is also a pumping action and where the term "propulsion device" is used in this specification and the following claims, it is intended to comprehend the pump also, since the action of the device in each case is the same.

In Figure 2, diaphragm 6 is preferably attached to the upper wall of tube 2 on all edges of the diaphragm. An exhaust tube 18 connects the rear end of expansion tube 2 to a condenser 19. A valve 20 is connected in tube 18.

Valve 12 is operated by sprocket 21, valve 20 by sprocket 23, and pump 25 by sprocket 22; and sprockets 21, 22, and 23 are preferably connected by a chain 24 in such a manner that valve 20 will be closed at the moment valve 12 opens. 40 Means such as a paddle wheel 26 may be connected to sprocket 21 by spokes 27 to rotate sprockets 21, 22, and 23 when the boat is in motion. Pump 25 is preferably used to draw the fluid up from the condenser through tube 28 and to force it back into boiler 9 through tube 29.

Preferably one or more elastic stopper bands such as bands 30 and 35, preferably having their foreward edges beveled and free to move, and their rear ends attached either to diaphragm 6 50 as shown for band 30, or to tube 1 as shown for band 35, are stretched tightly across the top of chamber 2 at spaced distances from its front edge. Said stopper bands will reduce the volume of the diaphragm inclosure necessary for closing 55

off intake 4 and will prevent excessive backflow of gas in chamber 2 before intake 4 is closed. Until stopper band 30 is pulled away from its contact with the top side of tube 1, by the downward motion of diaphragm 6, said stopper band will be pressed tightly against tube 1 by the compressed gas in the foreward end of the expansion chamber, and practically no gas will be allowed to pass backward until the foreward end of diaphragm 6 has expanded sufficiently to close off intake 4 to tube 1. Stopper band 35 has a similar action and function to band 30, the only difference being that the rear end of band 35 is attached to a wall of chamber 2 instead of to diaphragm 6. This will increase the useful backward thrust of diaphragm 6.

When high pressure gas is injected into tube 2 it is preferable to use a swinging, reinforcing backing 31, attached to the top foreward edge of tube 2, to support the foreward wall of diaphragm 6 against bursting.

The device illustrated in Figure 2 will operate similar to the one illustrated in Figure 1 except for the following. The exhaust gas from tube 2 will be transmitted through tube 18 to condenser 19 where the gas will be condensed to a liquid and pumped through tubes 28 and 29 back into boiler 9 where it will be reused.

The action of the device may be started by turning sprocket 21 by hand, or by other means, until propulsion tube 1 has had an opportunity to set the boat in motion. When the boat is moving the backflow of the water under the boat will continue to turn paddle wheel 26.

The speed of the boat will depend on the force and frequency of each injection of compressed gas into tube 2, and the energy of each injection will increase as the pressure in boiler 9 increases. Therefore the speed of the boat may be controlled by throttle 16 because the faster the fuel is supplied to the firebox the greater will be the pressure in the boiler.

To reverse the motion of the boat it is obviously only necessary to provide a system of tubes that will inject the gas flowing through valve 12 into tube 2 through tube 18 and that will exhaust the gas from tube 2 to tube 8 on up through valve 20.

In the drawing 32 is the floor, 33 the bottom, 50 and 34 the back of the boat, or of the container for the device.

Due to the fact that diaphragm 6 and the top of chamber 2 may be made of good insulating material the heat loss of the compressed gas will be small. In the device illustrated in Figure 2, where there is no loss of boiler fluid, a fluid having a low boiling point, and low heat of vaporization may be used to advantage. The size of chamber 3 may be made to contain a quantity 60 of water of such mass as will utilize the energy from tube 2 most efficiently. To explain more fully, if chamber 3 is made too short, the mass of the water therein will be so small that it will be forced out too rapidly for efficient propulsion 65 at ordinary boat speeds; and if chamber 3 is made too long the water friction against the walls of the tube will be excessive.

It will be observed that very few operating parts are necessary in the present invention and the mechanical losses ordinarily accompanying the use of screw propellers with gasoline or steam engines are entirely avoided.

My propulsion device owes its increased efficiency over present propulsion mechanisms chief-

ly to the features mentioned above. Because of its simplicity it will be inexpensive to make.

It is also evident that tube 1 may be made to extend a considerably shorter distance below the bottom of the boat than is required by an ordinary propeller blade. For this reason a boat equipped with my propulsion device may be made to navigate in shallower water than is ordinarily possible for small boats. Furthermore my propulsion tube will not be as damageable as the ordinary screw propeller.

No batteries or electric ignition system is necessary to this device.

It is not my intention to limit my device to the specific form shown and described in this application since other forms involving the same invention will suggest themselves upon reading the above specification.

Having described my invention what I now claim as new and desire to secure by Letters Patent of the United States is as follows:

1. In a propulsion device a propulsion tube comprising an expansion chamber having an inertia chamber joined thereto, a diaphragm disposed substantially across the expansion chamber and having its foreward edges tightly attached thereto whereby said chamber is divided into a plurality of longitudinal sections, a stopper band having one edge attached to the diaphragm and having a beveled free moving edge, said stopper band being disposed substantially across the expansion chamber a spaced distance from its ends, means whereby a compressed gas may be periodically injected into one section of the expansion chamber, and means whereby the gas may be exhausted from the expansion chamber.

2. In a propulsion device a propulsion tube comprising an expansion chamber having an inertia chamber joined thereto, a diaphragm disposed substantially across the expansion chamber and having all its edges tightly attached thereto whereby said chamber is divided into a plurality of longitudinal sections, a stopper band having one edge attached to the diaphragm and having a beveled free moving edge, said stopper band being disposed substantially across the expansion chamber a spaced distance from its ends, means whereby a compressed gas may be periodically injected into one section of the expansion chamber, and means whereby the gas may be exhausted from the expansion chamber.

3. In a propulsion device a propulsion tube having an expansion chamber, a diaphragm disposed substantially across the expansion chamber and having its forward edges tightly attached thereto whereby said chamber is divided into a plurality of longitudinal sections, a stopper band having one edge attached to the diaphragm and having a beveled free moving edge, said stopper band being disposed substantially across the expansion chamber a spaced distance from its ends, means whereby a compressed gas may be periodically injected into one section of the expansion chamber, and means whereby the gas may be exhausted from the expansion chamber.

4. In a propulsion device a propulsion tube having an expansion chamber, a diaphragm disposed substantially across the expansion chamber and having its foreward edges tightly attached thereto whereby said chamber is divided into a plurality of longitudinal sections, means whereby a compressed gas may be periodically injected into the forward portion of one section of the expansion chamber, whereby the expansive action of the diaphragm will first close off said portion of the

expansion chamber and thereafter force the liquid in the expansion chamber rearward as said diaphragm continues to expand progressively rearward, and means whereby the gas may be exhausted from the expansion chamber.

- 5 5. In a propulsion device a propulsion tube comprising an expansion chamber having an inertia chamber joined thereto, means whereby the expansion chamber is divided into a plurality of longitudinal sections, means whereby a compressed gas may be periodically injected into the forward portion of one section of the expansion chamber, whereby the expansive action of the diaphragm will first close off said portion of the expansion chamber and thereafter force the liquid in the expansion chamber rearward as said diaphragm continues to expand progressively rearward, and means whereby the gas may be exhausted from the expansion chamber.
- 10 10. 6. In a propulsion device a propulsion tube having an expansion chamber, elastic means whereby the expansion chamber is divided into a plurality of longitudinal sections, means whereby compressed gas may be periodically injected into the forward portion of one section of the
- 15 15. 7. In a propulsion device a propulsion tube having an expansion chamber, a diaphragm disposed substantially across the expansion chamber and having its forward edges tightly attached thereto whereby said chamber is divided into a plurality of longitudinal sections, a stopper band having one edge attached to the wall of the expansion chamber and having a beveled free moving edge, said stopper band being disposed substantially across the expansion chamber a spaced distance from its ends, means whereby a compressed gas may be periodically injected into one 20 section of the expansion chamber, and means whereby the gas may be exhausted from the expansion chamber.

GEORGE S. NELSON.

25

expansion chamber, whereby the expansive action of the elastic dividing means will first close off said portion of the expansion chamber and thereafter force the liquid in the expansion chamber rearward as said elastic dividing means continues to expand progressively rearward, and means whereby the gas may be exhausted from the expansion chamber.

5

7. In a propulsion device a propulsion tube having an expansion chamber, a diaphragm disposed substantially across the expansion chamber and having its forward edges tightly attached thereto whereby said chamber is divided into a plurality of longitudinal sections, a stopper band having one edge attached to the wall of the expansion chamber and having a beveled free moving edge, said stopper band being disposed substantially across the expansion chamber a spaced distance from its ends, means whereby a compressed gas may be periodically injected into one 20 section of the expansion chamber, and means whereby the gas may be exhausted from the expansion chamber.
